UNITED STATES PATENT OFFICE.

HENRY F. JOHNSON, OF MORGANTOWN, WEST VIRGINIA.

MOLD.

1,175,769.

Specification of Letters Patent. Patented Mar. 14, 1916.

Application filed June 28, 1915. Serial No. 36,794.

To all whom it may concern:

Be it known that I, HENRY F. JOHNSON, a citizen of the United States, residing at Morgantown, in the county of Monongalia 5 and State of West Virginia, have invented a new and useful Mold, of which the following is a specification.

The device forming the subject matter of this application is a mold structure adapted 10 to form a plurality of solid blocks of the sort commonly used in the making of a double wall, the structure being adapted for use primarily in connection with the slushing process, as distinguished from the 15 tamping process.

The invention aims to provide a mold so constructed that the finished product may be removed readily therefrom when the mold is inverted.

Another object of the invention is to provide novel means for interlocking the ends 20 of the mold sections and for mounting the partitions between the ends of the mold sections, so that the partitions will constitute 25 means for supporting the mold sections.

It is within the scope of the disclosure to improve generally and to enhance the utility of devices of that type to which the present invention appertains.

With the above and other objects in view 30 which will appear as the description proceeds, the invention resides in the combination and arrangement of parts and in the details of construction hereinafter described 35 and claimed, it being understood that changes in the precise embodiment of the invention herein disclosed can be made within the scope of what is claimed, without departing from the spirit of the invention.

In the accompanying drawing: Figure 1 40 shows the invention in top plan; Fig. 2 is a side elevation; Fig. 3 is a fragmental longitudinal section on the line 3-3 of Fig. 2; Fig. 4 is a transverse section on the line 4-4 45 of Fig. 2; Fig. 5 is a fragmental perspective showing a portion of one end of one section; Fig. 6 is a fragmental perspective showing the other end of the section. Fig. 7 is a fragmental end elevation showing one 50 of the end plates in place.

The present invention embodies end sections 1 and any desired number of intermediate sections 2, but three sections being shown in order to simplify the drawings, 55 although obviously, the molding structure herein described may comprise any desired

number of sections and may be of any length. Each of the sections preferably is a trough-shaped metal structure comprising a bottom 3 and resilient sides 4 which may 60 be sprung apart. The longitudinal edges of the sides 4 are turned outwardly to form beads 5. At one end of each section, the beads 5 hold projecting fingers 6 and at the other end of each section, the beads 5 are 65 open to form sockets 7 adapted to receive the fingers 6 of an adjoining section, all of the sections being alike.

The invention comprises a plurality of 70 metallic partitions or end plates, denoted by the numeral 8, each end plate 8 being provided with notches 9 which receive the fingers 6. Along their longitudinal edges, the end plates are bent upon themselves to 75 form reinforcing flanges 10.

In practical operation, the fingers 6 at one 80 end of each section are received in the sockets 7 on the end of an adjoining section, thus holding the several sections alined. The partitions are interposed between the 85 ends of the sections, the fingers 6 being received in the notches 9. The several sections thus are upheld by the partitions, it being noted at this point that, as shown at 15, the partitions 8 extend downwardly below the 85 bottoms 3 of the sections.

It is to be observed that the molding 90 structure hereinbefore described may be set up readily and with equal facility be taken down. When the product has set sufficiently, the end walls or partitions are removed, and the several sections are disconnected the fingers 6 being withdrawn from the sockets 7. The sections are then inverted 95 and the sides 4 thereof are sprung apart manually, thus separating each mold section from its contained product.

Having thus described the invention, what is claimed is:-

1. In a mold of the class described, a pair 100 of trough-shaped sections, one of which is terminally provided with sockets, the other of which is terminally provided with fingers received in the sockets; and a partition between the sections, the partition having 105 notches receiving the fingers.

2. In a mold of the class described, a pair 110 of trough-shaped sections, one of which is provided with sockets, the other of which is provided with fingers adapted to be received in the sockets; and a partition between the sections, the partition being pro-

vided with notches which receive the fingers, and being provided along its upright edges with reinforcements which engage the sockets.

3. In a mold of the class described, a pair of trough-shaped sections, one of which is provided with sockets, the other of which is provided with fingers received in the sockets; and a partition located between the sections, the fingers engaging the partition to uphold the sections, and the partition be-

ing downwardly extended below the bottoms of the sections to serve as a support for the sections.

In testimony that I claim the foregoing as my own, I have hereto affixed my signature in the presence of two witnesses.

HENRY F. JOHNSON.
